RECORDING MACHINE

Henry H. Barnard, Washington, D. C.

Application April 27, 1942, Serial No. 440,721

7 Claims. (Cl. 33—36)

The present invention relates to recording mechanism for applying on a record sheet any desired data, particularly by means of a series of lines.

It is an object of the invention to provide one or more recording units mounted on an adjustable frame. A further object resides in providing indicating means and line drawing or printing elements for each unit, preferably a pair of indicating and printing elements for each unit. A still further object of the invention resides in the provision of means for shifting all the units simultaneously a certain distance in a direction at right angles to the printing direction of the recorded lines.

Another object of the invention is to provide means for inking a printing roller for each printing element as the latter is adjusted to the position where the required lines are to be drawn. The printing rollers are each provided with means to print a so-called wavy or scalloped line to render it readily distinguishable from other lines to be manually recorded on a record sheet.

Further objects will be apparent from the following description taken in connection with the accompanying drawings in which,

Figure 1 is a plan view of the recording machine.

Fig. 2 is a cross-sectional view of the machine taken on line 2—2 of Fig. 1.

Fig. 3 is a cross-section taken on line 3—3 of Fig. 2.

Fig. 4 is a sectional view of a detail taken on line 4—4 of Fig. 2.

Fig. 5 is a side elevation of the adjusting device.

Fig. 6 is a plan view of the recording rollers.

Fig. 7 is a plan view of a portion of a record sheet.

The entire machine may comprise a panel or board 8 acting as a base frame or support. The board 8 has a dove-tail projecting rail 9, Fig. 2, along one side of the board which as seen in Fig. 1 may be termed the upper part or edge 10. This rail 9 receives a strip portion or slidable bar 11 having a groove 12 in the underside thereof which has a configuration similar to the dove-tail projecting rail 9, thus providing for a snug fit and a relative slidable movement. A rectangular frame 13 is hinged to the bar 11 by means of suitably spaced hinges 14. Along the bottom part 15 a short gear rack 16 is secured on the panel 8 which is adapted to cooperate with three pins 17, Figs. 1 and 5, rotatably mounted on a spindle 18 and having a knurled knob 19 to rotate the spindle and pins. The spindle 18

is mounted in a bearing bracket 20 secured on the frame 13. When it is desired to shift the frame 13 to the right or left, Fig. 1, it is merely necessary to manually rotate the knob 19 whereby one of the end pins 17 of the three, depending upon the direction of rotation, will pivot between two teeth of the rack 16, Fig. 5, to thereby shift and slide the frame 13 with its units in its entirety upon the dove-tail rail 9.

A plurality of indicating and recording units 21 are suitably secured on the frame 13 on the upper and lower members 22 and 23 by means of screws or the like, Fig. 2. Each unit 21 consists of a base bar 24 having a plurality of teeth 25 on the underside thereof in the form of a rack. A pair of recording and indicating devices 26 and 27 are mounted to slide on the bar 24 and each recording device is provided with a flat spring 28 which is adapted, by coiling action, to pull the device back to its end position, Fig. 2, when the devices are not in use. An end casing 29 houses the coiled spring and from which it uncoils from around the center pin 30 when the respective device 26, 27 is in use. Each casing 29 is suitably secured, by means of screws 31 for instance to the respective end of the bar 24.

Each recording and indicating device 26 and 27 is composed of a main U-shaped frame 32 which fits in an inverted position over the bar 24, Fig. 3. An auxiliary frame 33 of double U-shape fits on the main frame 32 by means of the actuating U-shaped branch 34 having a gear wheel 35 rotatably mounted therein. This gear wheel 35 is adapted to mesh with the rack 25. The other U-shaped branch 36 carries a printing roller 37 and an inking roller 38. A leg 39 is common to both U-shaped branches 34 and 36. A shaft 40 on which the gear wheel 35 is mounted also carries the printing roller 37 and both the gear wheel and printing roller 37 are securely mounted to rotate with the shaft 40 for the purpose which will be explained. An operating handle 41 is secured on the auxiliary frame 33 and a spring 42 between said frame and the main frame 32 forces the auxiliary frame and its rollers in the non-printing position.

The auxiliary frame 33 is provided with a pointer 43 which is slightly bent at an angle to point on or toward a record sheet 44.

If desired the top of the bar 24 may be provided with a strip 45 carrying a scale or other desired data or numbers.

It is also obvious that the printing roller may be provided to record one or more lines 46 as may be desired, as shown in Fig. 6, in which for

instance the unit 26 may print two lines and the unit 27 four lines.

The record sheet 44 in Fig. 7 shows a portion thereof in which the two lines 47 are printed by the roller of the unit 26 and the four lines 48 are printed by the roller in the unit 27.

A stop member 49 secured on the member 22 is for the purpose of maintaining the frame 13 in an upright position, dotted line position in Fig. 2, to remove or insert a record sheet.

In general the machine may be operated as follows.

In the positions of the parts of the units as shown in Figs. 1 and 2 are non-recording and the devices 26 and 27 are in their inoperative and non-indicating positions, each pair 26 and 27 of a unit 21 being pulled and held to each end of the bar 24 by means of its respective spring 28. If it is desired to record one or more lines 47 or 48, it is merely necessary to move the device 26 or 27 a short distance by the handle 41 without forcing the frame 33 down so that the gear 35 by means of the rack 25 will rotate the printing roller 37 to apply ink thereto and then where desired to start the printing, the frame 33 by means of the handle 41 is pressed down whereby the printing roller 37 will print a line or lines 47 or 48 on the record sheet 44. It will be observed that the rollers 37 while printing will be constantly inked, due to rolling contact with its inking roller 38.

As seen in Figs. 1 and 2, one way in which the machine may be used is for maintaining knowledge of and posting production of certain items, machines, units and assemblies, in which each block of rectangles represents monthly items, and in which the lines 48, Fig. 7, may indicate the quota to be reached each month, and lines 47 the actual number of items produced or completed. If, for instance, in some months the production may exceed the quota set therefor the lines which overlap will form a chain configuration where a form of lines 46 is chosen in which the small loops extend in opposite directions in the respective rollers 37 as seen in Fig. 6. It is obvious that each roller 37 may print one or any number of lines, and such lines may be straight or may comprise any desired configuration.

The shifting device 16 to 20 may be so constructed to laterally move the frame 13 and the units 21 any desired distance, such as one space represented by one longitudinal recording subdivision, as shown on the record sheet 44.

I claim as my invention:

1. A recording machine comprising a base support having a dove-tail projecting rail thereon, a bar having a dove-tail groove therein mounted on the support and slidable on the dove-tail projecting rail, a frame hingedly secured on the

bar and having an opening therein, and a line marking unit secured on the frame and adapted to draw a line through the opening in the frame on a record sheet on the base support.

5 2. A recording machine according to claim 1, in which means are provided on the support and the frame cooperating with the rail to shift the bar and frame a predetermined distance on the support.

10 3. A recording machine comprising a base support, a bar slidably mounted on the base support, a frame hingedly secured on the bar and having an opening therein, a line marking unit mounted and secured on the frame said unit having at least one indicating and recording device thereon and adapted to draw lines through an opening in the frame on a record sheet on said base support, and means for shifting the frame and unit on the base support including a gear rack and an actuating member.

15 4. In a recording machine having a frame movably mounted on a record sheet support, a recording unit mounted on the frame and comprising a base bar, an indicating and recording device slidably mounted on said base bar, a printing roller rotatably mounted in said device, an inking roller rotatably mounted in the device above and in contact with the printing roller, and means on the device and on the base bar to rotate the printing roller to provide ink thereon from the inking roller.

20 5. A recording unit according to claim 4, in which means are provided to pull the unit back to a non-recording position adjacent the frame after use.

25 6. A recording machine comprising a base support, a bar slidably mounted on the base support, a frame hingedly secured on the bar and having an opening therein, a line printing unit mounted and secured on the frame, said unit having at least one indicating and recording device thereon and adapted to draw lines through an opening in the frame on a record sheet on said base support, and means for shifting the frame and unit on the base support including a gear rack and an actuating member having three spaced pins which contact in the spaces between four gear teeth of the rack.

30 7. A recording unit for a recording machine comprising a base bar, a main U-shaped frame mounted to partially surround and to slide on the base bar, a U-shaped auxiliary frame mounted on and to partially surround the main frame and movable relative thereto, a printing device mounted in the auxiliary frame, and means on the base bar and mounted in the auxiliary frame to rotate the printing device upon sliding movement of the main frame.
